UNITED STATES PATENT OFFICE.

STANISLAW JAN ZALESKI, OF CHICAGO, ILLINOIS, ASSIGNOR TO SIMPLEX RAIL FASTENER & METALLIC TIE CO., OF CHICAGO, ILLINOIS, A CORPORATION OF ILLINOIS.

METALLIC TIE AND RAIL-FASTENER.

No. 917,832.

Specification of Letters Patent.

Patented April 13, 1909.

Application filed April 3, 1908. Serial No. 424,899.

To all whom it may concern:

Be it known that I, STANISLAW JAN ZALESKI, citizen of the United States, residing at Chicago, in the county of Cook and State 5 of Illinois, have invented certain new and useful Improvements in Metallic Ties and Rail-Fasteners, of which the following is a specification.

My invention relates to improvements in 10 metallic ties and rail fasteners; and the objects of my improvement are, first, the provision of a tie having a broad rail-bearing surface and a web of contour lines to be stable without the use of a base or flanges; 15 second, the employment of a clamp member capable of a rocking movement and a sliding movement toward and from the rail flange; third, the use of a brace-clamp to bear against the web of the rail; and, fourth, the 20 production of a soft iron wedge of such construction that when driven to position it will securely clamp the flange of the rail.

I attain these objects by the mechanism 25 illustrated in the accompanying drawings forming a part of this specification, in which—

Figure 1 is a side elevation of the tie and fastener assembled. Fig. 2 is a top plan view. Fig. 3 is a section on line 3—3 of Fig. 2. Fig. 4 is a cross-section on line 4—4 of Fig. 30. Fig. 2. Fig. 5 is a top plan view of the tie. Fig. 6 is an inverted plan view. Fig. 7 is a side elevation of a brace-clamp, and Fig. 8 is a vertical section of the same. Fig. 9 is a 35 perspective of the clamp-member. Fig. 10 is a perspective view of the wedge. Fig. 11 is a cross-section of the wedge. Fig. 12 is an inverted plan view of the tie.

Similar numerals refer to similar parts throughout the several views.

40 Referring to the drawings by reference numerals, 13 denotes relatively wide rail-bearing portions, and 14 a narrower intermediate portion of the tie. The web 15 of the tie has an incision or slit 16 a major portion of its 45 width and at right angle to the longitudinal axis of the web. The oppositely curved portions of the web, 17, 17^a, provide a stable base for the tie and prevent longitudinal displacement of the tie. The clamp openings 18, 19 through the top of the tie, it will be noted, are on opposite sides of the web. At right angle to the openings 18, 19 through the upper portion of the web and adjacent thereto are wedge slots 20. In opposite 50 edges of the top of the tie are depressions 21

which result in corresponding raised points to form guides for the wedge shown in Fig. 10.

The numeral 22 represents the rail. A clamp member 23, with rear extension 24, rear notch or recess 25, wedge opening 26, 60 and flange engaging portion 27, is adapted to be inserted in vertical openings 18 or 19 with the wedge opening 26 below the top of the tie. A somewhat similar brace clamp 28 is provided with rear extension 29, rear notch or 65 recess 30, wedge opening 31, offset 32, top of tie bearing surface 33, slightly rounded lower edge 34, web bracing upward extension 35, and flange engaging portion 36. The rounded edge 34 is adapted to permit a slight rock- 70 ing movement toward the web.

In Fig. 10 is shown a wedge preferably made of wrought iron or other metal capable of bending without fracture. The slots 20 in the web are preferably longer than the width 75 of the wedge, which is pointed, 39, beveled on one lower edge and has a head 37 for driving it into position and limiting its inward movement. It will be understood the edge 39 bears against one end of one of the slots 20, 80 and that the openings 26 and 31 are longer than the greatest width of the wedge.

In Fig. 1 the numeral 40 indicates the bent up point of the wedge.

In Fig. 12 is shown a modified form of web 85 formation. The ends 41 are similarly curved and the intermediate portions 42 are oppositely curved, with the incisions or slits 43, 43.

In the manufacture of my tie it may be rolled, the slits or incisions, 16, 43, made, and 90 the web oppositely curved in any suitable or desired manner to give it substantially the contour lines shown in the drawings.

In operation the flanges of the rail are placed on the tie between the opening 18, or 95 19, then the clamp members put into position with the flange bearing portion 27 upon the rail flange. The wedge (Fig. 10) is inserted through the opening 26 in the clamp member, or 31 of the brace clamp, and forced 100 to the desired position, and the point 40 turned up to avoid withdrawal. The brace clamp may be employed as often as may be required to brace the web of the rail from the outside side.

Variation in form, arrangement and construction as above described may be made, and I desire, therefore, not to limit my invention to the exact description of the preferred form in which it has been embodied.

105

110

2
Having thus fully described my invention, what I claim as new, and desire to secure by Letters-Patent, is—

1. In a metallic tie and rail fastener, in combination, a tie having a web oppositely curved laterally from a point intermediate its ends and horizontal slots therethrough, a clamp member having a wedge opening therethrough and a flange engaging portion, and a pointed wedge adapted to engage one end of one of the slots and the bottom of the wedge opening in the clamp member.

2. In a metallic tie and rail fastener, in combination, a tie having a web oppositely curved laterally from a point intermediate its ends and horizontally slotted near the top thereof, a brace clamp member having a wedge opening and an upper extension capa-

ble of bearing against the web and upon the flange of a rail, and a pointed wedge adapted to engage one end of one of the web slots and the bottom of the wedge opening.

3. In a metallic tie, a web having an incision at right angle to its longitudinal axis and oppositely curved from a point intermediate its ends to form a base, said web being curved near the incision at an angle to the length of the tie to prevent longitudinal displacement thereof.

In testimony whereof I affix my signature in presence of two witnesses.

STANISLAW JAN ZALESKI.
